[57] **CLAIM**

The ornamental design for an ornamental chain, as
shown and described.

DESCRIPTION

FIG. 1 is a front elevational view of an ornamental
chain showing my new design;

FIG. 2 is a side elevational view, the opposite side being
a mirror image;

FIG. 3 is a rear elevational view;

FIG. 4 is an enlarged cross-sectional view taken along
the lines 4—4 of FIG. 1; and,

FIG. 5 is an enlarged partial perspective view.
